[57] **CLAIM**

The ornamental design for a portable bar cabinet, as shown and described.

DESCRIPTION

FIG. 1 is a front elevational view of a portable bar cabinet showing my new design;

FIG. 2 is a top plan view thereof;

FIG. 3 is a bottom plan view thereof;

FIG. 4 is a right side elevational view thereof;

FIG. 5 is a rear elevational view thereof;

FIG. 6 is a front elevational view in open condition; the broken lines indicate environmental structure and form no part of the claimed design;

FIG. 7 is a rear elevational view thereof;

FIG. 8 is a top plan view thereof;

FIG. 9 is a bottom plan view thereof;

FIG. 10 is a left side elevational view thereof;

FIG. 11 is a right side elevational view thereof; and,

FIG. 12 is a view similar to FIG. 6, but without dotted lines.

FIG. 2

FIG. 5

FIG. 1

FIG. 4

FIG. 3

FIG. 6

FIG. 7

FIG. 8

FIG. 9

FIG. 10

FIG. 11

FIG. 12
